GEAR LAPPING AND FINISHING MACHINE

Joseph C. Drader and John D. Rovick, Detroit,
Mich., assignors to Michigan Tool Company, a
corporation of Delaware

Application August 24, 1935, Serial No. 37,671

6 Claims. (Cl. 51—26)

Our invention relates to gear finishing machines of the lapping, shaving and burnishing type.

While various methods and machines have been employed for lapping, burnishing and shaving gears, the present machine is a material advancement in the art of finishing gears in view of its accuracy and simplicity. The accuracy in finishing gears is produced by having the tool and gear moved during their relative operation from a position away from a correct center distance relation to such position or slightly beyond. Such movement functions as a feed of the gear into the tool, or vice versa. One or a plurality of tools may be employed, and the gear is preferably moved past the one or between the two tools from a position away from to a position on or slightly beyond the shortest radial relation therebetween. Such radial relation disposes the gear and tool or tools in correct center distance relation to each other. When cluster or herringbone gears are employed, two or more cutting tools may be utilized by preferably employing a tool on each gear portion of the cluster or herringbone gear. The machine may be made automatic to advance the gears between the two cutting tools, in which instance the gear would be fed at a rapid speed into mesh with the two gears, after which it will be slowly fed therebetween to a position on or slightly beyond the center line between the two tools. Thereafter the carriage would again move rapidly to bring another gear into mesh relation with the tool. In this manner the machine may be continuously operated and the gears rapidly passed therethrough to be accurately finished.

Accordingly, the main objects of our invention are: to provide a simplified machine for accurately finishing gears to proper tooth form and diameter; to provide a machine having a single tool which may be fed relative to the gear to have the gear machined to a proper diameter when the tool is fed to or beyond a plane through the center line of the gear normal to the tool feed movement; to provide a machine with two tools which are spaced apart such a distance that gear passing therebetween will be finished to accurate dimensions; to provide a machine in which one of the tools is driven for driving the gear and the second tool, the latter of which may have a brake applied thereto, to construct the machine to have the tools mounted to be tilted to a position at an angle to the plane of the gear; to provide a plurality of tools in different planes either laterally, angularly or both to operate on different gears of a group; to provide a machine which automatically feeds the gears between the two tools to have a continuously operating machine; and in general, to provide a machine for finishing gears which is simple in construction, ac-

curate in machining and economical of manufacture.

Other objects and features of novelty of our invention will be either specifically pointed out or will become apparent when referring, for a better understanding of our invention, to the following description taken in conjunction with the accompanying drawings wherein:

Fig. 1 is a view, partly in section and partly in elevation, of a machine embodying features of our invention;

Fig. 2 is a plan view of structure illustrated in Fig. 1;

Fig. 3 is a view of structure, similar to that illustrated in Fig. 2, showing a modified arrangement of the tools and gears;

Fig. 4 is a view of structure, similar to that illustrated in Fig. 1, showing a modified form thereof;

Fig. 5 is a view of structure, similar to that illustrated in Fig. 4, showing a further modified form of our invention;

Fig. 6 is a broken view, in elevation, of a machine for continuously machining gears which are fed therethrough;

Fig. 7 is a sectional view of the structure illustrated in Fig. 6, taken on the line 7—7 thereof;

Fig. 8 is an enlarged sectional view of the structure illustrated in Fig. 7, taken on the line 8—8 thereof;

Fig. 9 is a plan view of a right and left hand spiral tool operating on a spur gear;

Fig. 10 is a view in elevation of a pair of tools disposed in relation somewhat similar to that illustrated in the machine in Fig. 1, showing the gear moved on an arc between the tools;

Fig. 11 is a view of structure, similar to that illustrated in Fig. 5 with the gear moved on an arc, inwardly presented relative to the tool;

Fig. 12 is a view of structure similar to that illustrated in Fig. 11, with the gear moved on an arc, outwardly presented relative to the tool; and

Fig. 13 is a view of structure in which the principles utilized in the structure of the above figures are employed for finishing internal gears.

Fig. 1, we have illustrated a finishing machine comprising a base 11 supporting a motor 12 for driving a fluid pump 13 which operates the machine. The base supports ways 14 in which carriages 15 are shiftable by means of lead screws 16 and clamped into position by suitable bolts 17. The carriage 15 on the right hand side of the figure is provided with a fluid motor 18 which drives a shaft 19 in rotation. The shaft drives through gears 21, a shaft 22 and a worm 23 which rotates the worm wheel 24. The worm wheel 24 is mounted on a shaft 25 on which the tool 26 on the right hand side of Fig. 1 is mounted. The motor 18 is rotatable within a head 27 on the

carriage 15 to permit the tool 26 to be disposed at various angles relative to the gear 28 to be machined, as illustrated in Fig. 2. The carriage 15 on the left hand side of the figure may be constructed in the same manner as that on the right hand side, and carries a head 31 provided with a suitable internal fluid brake (not shown), for applying a load on the tool 26 mounted thereon. In the present instance, the tool 26 at the left of Fig. 1 is illustrated as being mounted journaled in the shaft 29 on a head 31, which is secured by a bolt 32 to the upstanding portion of the carriage 15 for adjustment about the axis of the bolt to permit the tool to be shifted to a predetermined angle relative to the gear 28 as illustrated in Fig. 2. In this construction the teeth of the tool 26 are of mating width so that both sides of the teeth are machined during the advancement of the gear 28 therebetween. When a burnishing or lapping operation is to be performed, the teeth of the tool may be thinner than required for mating relation with the teeth of the gear and for this reason a brake is employed to have the driving side of the driving tool 26 operate on one side of the teeth of the gear while the teeth on the opposite loaded tool 26 operate on the opposite sides of the teeth of the gear.

The base 11 also supports a column 33 centrally of the machine between the two tables 15. A carriage 34 is slideable on the column through the adjustment of a lead screw 35 and is provided with a horizontally extending portion 36 on which a carriage 37 is mounted for horizontal adjustment. This is effected by means of a hand wheel 38 which operates a lead screw which is attached to the carriage 37. The carriage 37 supports bosses 39 and 41 in which centers 42 and 43 are mounted to function as head and tail stocks for securing the gear 28 in position. The adjustment of the carriage 37 by means of the hand wheel 38 aligns the gear 28 with the tools 26 and through the adjustment of the lead screw 35 the tool 26 is fed from a position above or below the center line between the tools to a position on or below or above, respectively, the center line between the tools.

Through the angular disposition of the tools relative to the gears a lateral component of movement is provided between the teeth of the gear and tool which, during the machining operation, tends to compensate for the deforming of the gear teeth due to roll. Such deforming on the roll is entirely eliminated when employing a tool having teeth provided with cutting edges similar to those described and claimed in the co-pending application of W. F. Dalzen, Serial No. 554,193, filed July 13, 1931, and assigned to the assignee of the present invention.

Machining is produced by the lateral component of movement to cut uniformly at the crown, through the pitch line and the root of the teeth, thereby accurately forming the teeth to true involute shape. While some methods employed in the art rely upon an additional lateral feed movement between the tool or tools and the gear, in the present instance such feed may be eliminated since the particular relative movement from off to on center position of the gear and tool is sufficient to produce accurate machining and tooth form. We have illustrated, in Figs. 1 and 2, a spur type of gear employing a spiral type of tool, the angle being such as to produce a substantial balance between the amount of cutting due to the roll and due to the lateral component of slippage to thereby lap or burnish

substantially a uniform shape to the teeth. When shaving is employed, the cutting edges are so disposed as to cut only due to the lateral component of movement between the angularly disposed teeth of the tool and the straight teeth of the gear which thereby cut uniformly from the crown, through the root and pitch line of the gear teeth.

While this angle may vary, depending upon the type of the gear and teeth to be machined, it is to be understood that the angle may be any size desired even though spiral teeth are disposed on the gear 28 in place of the spur type teeth. The teeth on the cutting tool are preferably plus and minus the angle of the teeth on the gear. That is to say, if the teeth of the gear are disposed on a forty-five degree (45°) angle, the one cutting tool may have the teeth disposed at an angle of thirty degrees (30°) while the other tool may have the teeth disposed at a sixty degree (60°) angle, the angular difference in the planes of operation of the gear and tools being fifteen degrees (15°). This angular difference may vary and can be obtained by changing the angular relation of the teeth.

In Fig. 3, we have illustrated the gear as being of the herringbone type, having two gear segments with the helix angle of the teeth disposed in the opposite hands. One cutting tool operates on one of the segments, while the other tool operates on the other segment of the gear. The machine is otherwise operated in accordance with the above described manner. To effect the adjustment of the tools laterally, ways 30 are provided on the carriage 15 which permits the heads 27 and 31 to be adjusted laterally of the plane through the gear to operate on different segments of the herringbone gear, as illustrated. It is to be understood that it is within the purview of my invention to employ the two tools on each of the separate segments of the herringbone gear following the exact teaching of the structure illustrated in Figs. 1 and 2.

On a cluster type of gear the same arrangement obtains as on a herringbone gear. Two tools may operate on a single gear of the cluster or one tool may operate on one gear of the cluster while one or more additional tools operate on the one or more additional gears of the cluster. In any of the arrangements, the driving of the tools and gear may be reversed by simply reversing the flow of the fluid through the motor, either by reversing the driving motor of the pump or by reversing the valve controlling the flow of fluid through the motor.

In Fig. 4, we have illustrated a modified form of the machine illustrated in Fig. 1, wherein the carriage 15 at the left-hand side of the figure, as viewed in the drawing, has a spring 46 interconnected between the carriage support 14 and the carriage to urge the carriage toward the gear to force the tool into intimate engagement therewith. In this construction the exact centering of the gear 28 relative to the tool 26 is effected between the two shafts of the gear and tool, while the shaft of the tool which is spring pressed need not be accurately located since the spring will force it into intimate contact with the gear. In this manner the same results will obtain as when practicing the invention illustrated in Figs. 1 and 2 while at the same time the difficulty of accurately locating the second tool relative to the axis of the gear is thereby eliminated.

In Fig. 5, we have illustrated a form of machine which may be employed when only a single tool

is utilized. This machine will operate in the same manner as that illustrated in Fig. 4 when the tool which is spring pressed is eliminated. In the present construction a single support 14 is utilized for the carriage 15 and head 27, which follows the construction of the head illustrated in the foregoing figures. Oppositely disposed to the support 14 is a column 48 which projects from the base 11 carrying ways 49 on which a carriage 51 is movably adjusted by a lead screw 52. The carriage 51 supports a carriage 37 having a head and tail stock similar to those described above relative to structure illustrated in Figs. 1 and 2. In the figure, we have illustrated the axis of the gear and tool as being on correct center distances after the tool has been fed downwardly from a position above that shown to a position of correct center distance relation, which is the position in which the gear is completely machined. During the downward feeding of the gear to correct center distance relation with the tool, the machining of the teeth will take place due to the driving of the tool 26 which machines the teeth during the downward feeding movement.

Referring to Figs. 6, 7 and 8, we have shown a further form of the invention wherein an automatic machine is provided wherein the gears are continuously brought into engagement with the tools and fed therethrough during the machining of the teeth thereof. A carriage 15 is provided with a head 27 for supporting a fluid motor which drives a tool supporting shaft 66. Similarly, the base of the machine which supports the head 27 also supports an upright 58 carrying a movable element 59 shiftable by a lead screw 61.

A shaft 62 is carried in suitable bearings 63 on the element 59 for supporting a tool 64 and a gear 65. The shaft 66 is carried in suitable bearings 67 and 68 on the base 11 for supporting a second tool 69 in aligned spaced relation with the tool 64. The shafts are interconnected by a train of gears 11 for maintaining the driving of the tool in synchronized relation. The train of gears is so mounted as to permit the adjustment of the two cutting tools 64 and 69 toward and away from each other to conform to the diameters of different gears to be machined.

A pair of spiders 72 are mounted on opposite sides of the tool 69, having hubs which engage the shaft 66. The spiders support projecting arms 73 which are retained together by pins 74 which also support arms 75 that are urged inwardly toward the shaft 66 by springs 76. The arms 73 are provided with slots 77 for receiving a shaft 78 on a gear 79 to be machined. The hub of the right-hand spider 72 is provided with a gear 81 which meshes with a gear 82 mounted on a shaft 83 in extension of one of the gears of the train 11. The driving of the gear 81 through the gear 82 and the shaft 83 from a slowly operating gear of the train, provides a feed movement of the spiders which slowly advances the gears 79 between the toothed tools 64 and 69. A clutch 84 is provided on one side of the gear 81 operated by a plurality of cams 85 on the opposite side of the gear 81 which periodically engage an element 86 to lock the gear to the shaft 66 to have the spiders and gear rotate with the tool 69. The operation of the clutch advances a gear from finished position to unloading position, and advances another gear from loading position into mesh with the tools where they are advanced by the feed movement above mentioned. An overrunning clutch 87 permits the rapid advancement of the gear 81 relative to the shaft 83.

At the loading position, a stop 88, which may be suitably stationarily supported upon the machine frame, is employed to engage the shaft 78 of the gear to prevent the gear from coming into mesh with the teeth of the tool 69 until after the gear has been advanced from loading position. Thereafter the spring pressed arms 75 will move the gear to be machined into mesh with the teeth of the tool 69. The gear is then running in synchronism with the tool 69 and since the tool 64 is running in synchronism with the last named tool, the gear will fall into mesh with the teeth of the gear 64 when rapidly advanced into machining position.

A sloping element 89, also suitably supported upon the machine frame, is positioned at the unloading station to engage the ends of the shaft 78 of the gear to cause it to move out of the slot 77 against the bias of the arms 75 to be ejected from the machine. It is only necessary for the operator to dispose a gear in the slot 77 after the arm 75 has been drawn therefrom and release the arm to permit it to engage the shaft of the gear to force the gear onto the stop 88 and thereafter to force the gear into mesh with the teeth of the tool 69 when the spider is advanced away from the stop position.

The driving of the tool 69 is effected in the manner above pointed out through the operation of the motor in the head 27 and the continued actuation of the machine is thereby effected. As soon as the gear has reached a center-line position between the two tools 64 and 69, one of the cams 85 will cause the finger 86 to throw in the clutch to advance a new gear into position to be machined and be fed to or beyond tool center line position through the operation of the shaft 83 and gears 82 and 81. When gears of different diameters are to be machined, the tools 64 and 69 may be adjusted closer together or farther apart, as the case may be, the disposition of the train of gears 11 being such as to permit such adjustment while maintaining the operating relation of the gears. The elements 73 are adjustable radially of the spiders 72 through the engagement of a slot with a clamping bolt 91. A machine for lapping, burnishing or shaving gears may be constructed in this manner and continuous operation of the machine is thereby provided to have the gears automatically advance into machining position and slowly fed through the tools without stopping or adjusting the machine.

The machine just described has the gear and tools disposed in the same plane with the parallel axes. The machine illustrated in Figs. 1 and 2 could have gear supports mounted on an endless belt to advance the gears between the tools 28 in the same manner. This would provide an automatic machine in which the tools are tiltable relative to each other and the gear. It is also to be understood that the table for supporting the gear can be machine-fed through the tools rather than hand-fed, as illustrated in Figs. 1 to 5.

In Fig. 9, we have illustrated a pair of tools 81 and 82 operating on a roughed out gear 93. The gear may be mounted in the machine as illustrated in the various figures and operated in the manner set forth hereinabove. It will be noted, however, that the gears 81 and 82 are in the same plane, or substantially so, caused by the gears being of opposite hands to each other. That is to say, if the tool 81 has teeth disposed on a right hand helix, the teeth on 82 will be disposed on a left hand helix. In this manner the tools will tilt in the same plane if the helix

angles are equal. If the helix angles are different the tools will tilt on the same side of the plane of the gear but will be tilted at different angles relative thereto. Advantages in the machining of the gear are provided when employing tools of opposite hand as illustrated.

In Fig. 10, we have illustrated a pair of tools 94 and 95 between which a gear 96 is moved on an arcuate path 97. The tools 94 and 95 are supported in a machine similar to that illustrated in the figures of the drawings, disposed relative to each other in accordance with the diameter of the gear to be machined and tilted at desirable angles relative thereto. The support for the gear differs from the support for the gear illustrated in Fig. 1, in that the gear is moved in an arcuate path following the arc 97 the same as that of the gear in the machine illustrated in Fig. 6.

A single tool 94 is employed in the structure illustrated in Fig. 11, the gear following a curved path which is inwardly presenting relative to the tool 94. A tool 95 is employed in the structure illustrated in Fig. 12, the gear 96 following the curved path 97 which is outwardly presenting relative to the tool 95. Further advantages are provided when operating a gear and tool when disposed as in the structure illustrated.

In Fig. 13, we have illustrated the above principles of meshing gears applied to the finishing of internal gears. In the structure illustrated, an internal gear 98 is operated on by a tool 99. The tool is mounted eccentric to move on an arc 100 to have the teeth of the tool advance in depth into the teeth of the gear during the time one is driven relative to the other. In any instance, the lateral or arcuate movement of the gear or tool relative to each other is that to produce a movement between the teeth of the gear and tool from slight contact to full contact during the relative driving thereof. The gear is preferably mounted to tilt so as to be disposed at an angle to the tool. Such movement of the gear and tool relative to each other should occur at least until the teeth exactly mate, that is to say, until the axes of the gear and tool are on exact center distance. Preferably the gear and tool are moved beyond this position as is necessary in some of the structures illustrated. It is to be also understood that the operation of the gear and tool when only a single tool is employed is such that the direction of rotation is reversed so that machining will occur on both sides of the teeth of the gear. In this construction, the gear is preferably moved from a position of slight contact through a position on correct center distance, and finally to a position of slight contact beyond the center position, whereupon the direction of rotation is changed and the feed operation repeated so as to thereby machine both sides of the teeth.

While we have described and illustrated several embodiments of our invention, it will be apparent to those skilled in the art that various changes, omissions, additions and substitutions may be made therein without departing from the spirit and scope of our invention, as set forth in the accompanying claims.

We claim as our invention:

1. A machine for finishing gears to accurate dimension including, in combination, a rotatable gear-like tool, means for driving said tool in rotation, means for advancing a gear to be machined by said tool along a line substantially par-

allel to a tangent to the tool adjacent the point of machining contact from a position "away from" to a position at least "on" a line normal to said tangent which passes through the axis of the tool, and a second tool likewise positioned to have the gear pass through the center line through the tools normal to said tangent.

2. A machine for finishing gears to accurate dimension including, in combination, a rotatable gear-like tool, means for driving said tool in rotation, means for advancing a gear to be machined by said tool along a line substantially parallel to a tangent to the tool adjacent the point of machining contact from a position "away from" to a position "on" a line normal to said tangent which passes through the axis of the tool, a second tool likewise positioned to have the gear pass to the center line through the tool normal to said tangent, and means for applying a braking load to the last said tool.

3. A machine for finishing gears to accurate dimension including, in combination, a rotatable gear-like tool, means for driving said tool in rotation, means for advancing a gear to be machined by said tool along a line substantially parallel to a tangent to the tool adjacent the point of machining contact from a position "away from" to a position "beyond" a line normal to said tangent which passes through the axis of the tool, a second tool likewise positioned to have the gear pass to the center line through the tool normal to said tangent, means for applying a braking load to the last said tool, and means for shifting said tool laterally of a plane through the gear.

4. A machine for successively finishing a plurality of gears comprising in combination a rotatable gear-like tool, means for driving said tool in rotation, a rotatable fixture adapted to support a plurality of gears in spaced relation around the periphery thereof, means for supporting said fixture so that the rotation thereof causes said gears to be successively moved into and beyond a position of machining contact with said tool, and periodically operable means actuated by said driving means for rotating said fixture.

5. The method of finishing gears which comprises meshing a gear member to be finished with a gear-shaped finishing member having teeth conjugate to the teeth of the gear member, with the axes of said members crossed at an angle less than 30°, rotating one of said members thereby driving the other member and translating one of said members relative to the other in a plane which contains the axis of said member and which plane is parallel to the axis of said other member, and in a direction generally perpendicular to the axis of said gear member.

6. The method of finishing gears which comprises meshing a gear member to be finished with a gear-shaped finishing member having teeth conjugate to the teeth of the gear member, with the axes of said members crossed at an angle less than 30°, rotating one of said members thereby driving the other member and translating one of said members relative to the other in a plane which contains the axis of said member and which plane is parallel to the axis of said other member and in a direction making an angle of at least 60° with the axis of said gear.
